PROCESS OF MAKING DISKS FOR CENTRIFUGAL SEPARATOR BOWLS

Theodore H. Miller, Poughkeepsie, N. Y., assignor
to The De Laval Separator Company, New York,
N. Y., a corporation of New Jersey

Application September 21, 1933, Serial No. 690,412

4 Claims. (Cl. 29—148.2)

My invention relates to disks for the bowls of centrifugal machines and comprises an improved process for making such disks and for improving the disks themselves.

In order to divide liquids being separated or purified in centrifugal machines into thin layers, the bowls are usually provided with liners composed of a number of thin metal frusto-conical members known in the art as disks, which are kept at the correct distance apart by projections, called caulks, on one or both sides. These caulks generally are made of thin pieces of metal soldered or welded to the disk proper. This construction, formed of many pieces (disks often have from 12 to 30 caulks) fastened together, is expensive. When caulks are soldered on tinned disks, the heat causes marks on the opposite side. When they are spot welded before tinning, flux between them and the disk prevents entrance of tin and leaves a space that is unsanitary.

Disks made of the recently developed stainless steels would have many desirable features, but this material cannot be soldered and the heat necessary to weld so changes the structure of the steel as to destroy its stainless properties.

The object of my invention is to make a disk of one piece of metal, preferably stainless steel, with no seams and by a process which effects no changes in the physical structure of the metal.

In making such a disk, I first form a disk blank of thick material having the desired body shape, then emboss spots to raise on one side projections of the shape and height desired for caulks, and then remove from the other side metal of a thickness at least equal to the depth of the indentations made while embossing, thus leaving a smooth surface on the side opposite to the caulks.

I prefer to form the disk blank in the manner described in the Lindgren Patent No. 1,939,535, dated December 12, 1933, in which the thickness measured in a line parallel to the axis of the disk is the same for the frusto-conical portion as for the flange portions but the blanks may be made in any approved manner.

I know that it is old to provide caulks on disks by embossing to form projections on one side and corresponding indentations on the other side; but caulks formed in that manner have such narrow lines of contact with the adjacent disk that wear is very rapid, or alternate disks must have caulks in different locations. The indentations opposite the caulks are also harder to clean than a smooth surface.

I also know that it is old to make a one piece disk by bending around and folding back on the

body of the disk, metal that would otherwise be cut off and thrown away as scrap (see Leitch Patent No. 1,160,624); but this leaves crevices that, unless filled with tin or other material, are impossible to clean and hence very unsanitary.

In the accompanying drawing, which illustrates successive steps in the new process of manufacturing the improved disk,

Figure 1 is a cross section of a disk blank made by the aforementioned Lindgren process.

Figure 2 is a similar section of a blank with one caulk embossed therein.

Figure 3 is a similar section of three completed disks nested together, the inner side of the lower disk being shown. This section is taken close to the near side of the caulks on the inner and outer flanges.

I first form the blank shown in Fig. 1, wherein *b* is the disk body, *a* is the inner flange and *c* the outer flange. The flanges are shown as extending in planes at right angles to the center line; though they may be in the form of frustums of very broad cones turned either upward or downward, as shown by the dotted lines on the outer flange.

By embossing or deformation I then form projections *e* on one side of the disk body, leaving indentations *d* on the other side. From the latter side material is removed to the depth of the line *f*, Fig. 2, which is flush with, or below, the bottom of the indentations *d*, so that this side of the disk presents a smooth surface unbroken by indentation or projections. From the flanges *a* and *c* is removed material to the depths of the lines *g* and *h* respectively, Fig. 2, throughout all the area thereof except at points at which it is desired to have caulks. There is thus formed a disk, three of which are shown in Fig. 3, comprising a frusto-conical body *b'*, an inner flange *a'* and an outer flange *c'*; the body having frusto-conical caulks on its under side, the flange *a'* having caulks *i* on its upper side, and the flange *c'* having caulks *j* on its lower side.

In reducing the thickness of the disk from that of Figs. 1 and 2 to that of Fig. 3, the disk may be put in a lathe, a grinder, or some other metal-removing device, and the material above the broken line *f* removed, leaving the outside of the frusto-conical portion smooth. The material on the flanges *a* and *c* between the desired caulks may be removed by filing, cross milling, or rotating under a mill, which, at the desired locations for caulks, is raised to skip the caulk metal. By these, or any other workable procedure performing the same function, there is produced a

complete one-piece disk with caulk formed from the original blank and having no crevices, indentations, projections or other irregularities that would be inaccessible for easy cleaning.

5 As an alternative procedure caulk may be formed on the flanges, as well as on the frustro-conical body, by embossing to make projections on one side and by removing metal to the bottom of the indentations on the other side.

10 I do not herein claim the herein described disks. Such disks form the subject-matter of a separate divisional application filed December 18, 1934, Serial No. 758,003.

15 What I claim and desire to protect by Letters Patent is:

1. The process of making centrifuge disks with integral caulk which comprises forming a disk having a thickness not less than the desired finished thickness of the disk body and caulk combined, embossing the disk to form caulk on one side thereof, and removing metal from the major portion of the surface on the other side to such depth as makes the surface of said other side substantially smooth.

20 2. The process of making centrifuge disks with integral caulk which comprises forming a disk substantially thicker than the finished disk, embossing to form caulk on one side and complementary indentations on the other side, and re-

moving metal from the major portion of the surface of said other side to a depth not less than the depth of said indentations.

25 3. The process of making centrifuge disks with integral caulk which comprises forming a disk with a frustro-conical body and internal and external flanges, embossing the frustro-conical body to form caulk on one side, removing sufficient metal from the other side of the frustro-conical body to provide, opposite the caulk, a smooth 10 surface flush with the remaining surface of that side of the body, and removing metal from spaced-apart portions of the flanges while leaving, between said spaced apart portions, metal 15 to form caulk.

30 4. The process of making centrifuge disks with an integral caulk which comprises forming a disk blank having a thickness substantially greater than the desired height of the caulk above the 20 face of the disk adjacent thereto, embossing the disk to form on one side a caulk of the specified height and on the other side an indentation of less depth than the thickness of the blank, and removing metal from the major portion of the 25 surface of the indented side of the blank to a depth not less than the depth of said indentation.
